UNITED STATES PATENT OFFICE.

FRANK L. CASSELBERRY, OF PHILADELPHIA, PENNSYLVANIA, ASSIGNOR TO
EUGENE IVINS, OF SAME PLACE.

DESIGN FOR A BISCUIT.

SPECIFICATION forming part of Design No. 25,243, dated March 10, 1896.

Application filed January 6, 1896. Serial No. 574,550. Term of patent 3½ years.

To all whom it may concern:

Be it known that I, FRANK L. CASSELBERRY, a citizen of the United States, residing at the city of Philadelphia, in the county of Philadelphia and State of Pennsylvania, have invented and produced a certain new and original Design for a Biscuit or Similar Article, of which the following is a specification.

The leading feature of my design consists of a biscuit or similar article having a body or background outlining the numerals "96," with scalloped or spear-shaped configurations at the top and bottom between the disposition of said outlined numerals appearing within or upon said body or background.

In the accompanying drawings, forming part hereof, Figure 1 is a top or plan view of a biscuit or similar article embodying the features of shape or form and ornamentation of my present design; and Fig. 2 is a vertical sectional view on the line $x-x$ of Fig. 1 through the body or background having the shape or form of the configuration of the design of my said invention associated therewith.

Referring to the drawings, A represents

the body or background of the biscuit or the like, outlining as to shape or form the numerals "96," which join each other at the point a , and between them at the top and bottom are scalloped or spear-shaped portions b and b' , as clearly illustrated in Fig. 1; but the said portions b and b' may be omitted without affecting the scope of my design. The lines defining the said numerals are represented by the letters c and c' , while the spaces between the numerals are represented by the letters d and d' .

Having thus described my invention, what I claim as new, and desire to secure by Letters Patent, is—

The design for a biscuit or similar article, substantially as shown and described.

In testimony whereof I have hereunto set my signature in the presence of two subscribing witnesses.

FRANK L. CASSELBERRY.

Witnesses:

THOMAS M. SMITH,
RICHARD C. MAXWELL.
